METHOD OF EXTRACTING PHENOLS AND
THE LIKE

Ralph H. McKee, Jersey City, N. J.

No Drawing. Application April 8, 1927, Serial
No. 182,181. Renewed December 28, 1932

18 Claims. (Cl. 260—154)

This invention relates to a process of separating certain ingredients of oils from the other ingredients occurring therewith in such oils, and more particularly to a process of extracting "tar acids" or phenols from "tar oil".

A principal object of this invention is to provide a simple and economical process of extracting and isolating certain of the substantially water insoluble ingredients from oils such as "tar oils", naturally occurring petroleum oils, shale oils, and the like by treating such oils with a solution of an organic material capable of dissolving such ingredients when the solution is in concentrated form but incapable of dissolving to a substantial extent or retaining such ingredients in solution when the solution is in dilute or weak condition.

A further object of this invention is to provide an efficient process for extracting certain ingredients such as "tar acids" or phenols, certain hydrocarbons such as benzol, naphthenic acids, nitrogen base compounds and the like from oils such as "tar oils", petroleum oils, shale oils and the like by treating such oils with a strong aqueous solution of an organic material capable of dissolving such ingredients when the solution is in concentrated form, diluting such solution to separate out such ingredients in substantially unchanged condition, and recovering such ingredients.

A further object of this invention is to provide a process of extracting certain ingredients which are but slightly soluble in water from oils by treating such oils with a strong aqueous solution of an organic salt capable of dissolving such ingredients when the solution is in concentrated form and recovering the ingredients from such solution.

A further object of this invention is to provide a process of extracting "tar acids" or phenols from "tar oils" by treating such oils with a strong aqueous solution of sodium cymene sulfonate.

Other objects and advantages of this invention will be apparent during the course of the following description.

While the process forming the subject matter of this invention is applicable to the extracting of ingredients of the character referred to herein it is particularly adapted for use in connection with the extraction of "tar acids" from "tar oils" and this particular application of the process is described as the preferred embodiment of the invention. It is to be understood, however, that the invention is not limited to such application of the process.

Heretofore "tar acids" have been removed or extracted from the "tar oil" which is obtained by redistilling tars which are obtained in the distillation of coal, by treating the "tar oil" with a solution of caustic soda, usually of approxi-

mately 10 per cent. strength. Such solution is then separated from the remaining insoluble portion of the oil and is then treated with a sufficient amount of an acid, usually sulphuric or carbonic, to completely neutralize the caustic soda. The "tar acids" or phenols are then separated out and are drawn off and purified by distillation. In this procedure the caustic soda reacts with the phenols present in the oil to form sodium phenolates which are soluble in water. The solution of sodium phenolates is then treated with an acid to form the sodium salt of the acid and free phenols. This process is expensive due to the complete loss of the caustic soda and the acid employed and the minor difficulties attendant upon the recovery of the phenols from the milky solution obtained on precipitation with the acid. Moreover this process involves handling acids and strong caustic material which is a distinct disadvantage.

I have discovered that the mixture of crude phenols obtained from low temperature tar distillation and the similar mixture of phenols obtained from high temperature distillation while substantially insoluble in water are readily soluble in a concentrated aqueous solution of ammonium acetate, sodium benzene sulfonate, sodium cymene sulfonate, sodium naphthenates or in various other salt solutions as well as in solutions of organic materials which are not salts of true acids, or in aqueous solutions of some acids such as benzenesulfonic acid, or in mixtures of such solutions. The organic materials which are not salts or true acids and the above mentioned acids, such as benzenesulfonic acid, are to be considered equivalents of the organic salts of the character referred to. I have also discovered that on simple dilution of these solutions of phenols the phenols will separate out leaving the dilute solution substantially free from such phenols. Furthermore on evaporation of this aqueous solution any small amount of phenols remaining therein will distill off with the steam and can be recovered in the distillate. A distinct advantage of this procedure is that the resulting solution after being concentrated back to its original strength can be used again for dissolving additional phenolic tar acids.

In the preferred practice of my process I prefer to employ a relatively strong solution of an alkali sulfonate, such as sodium cymene sulfonate preferably a one-half saturated solution or stronger, and this solution may be either neutral, alkaline, or acid without affecting the desired result except that if more strongly alkaline than a pH of 13 only a part of the phenols will be recovered on dilution. When a tar oil obtained by the distillation of coal tar is brought in contact with such a solvent its phenolic tar acid content is dissolved in the aqueous solution leaving

the hydrocarbons and other insoluble products in the residual oil. The aqueous solution carrying the "tar acid" is then diluted with water, the water being added preferably in an amount equal to about one-half of the volume of the solution, the exact proportion of water to be added depending on the original concentration of the solvent solution, on the solute employed in the solvent solution, on the material being dissolved, and on the temperature of operation. The tar acid separates out and is drawn off or recovered in any suitable manner. The aqueous solution is then evaporated until it has reached its original concentration when it may be again employed for dissolving additional amounts of tar acids.

In the preferred practice of the process a plate and cap column such as is used in the distillation industry is employed and the extracting solution is fed in at the second or third plate from the top of such plate and cap column. The tar oil to be treated is introduced at the first or second plate above the bottom of the apparatus. The whole column is filled with the liquids and the process is a continuous counter-current one, the aqueous extracting solution carrying approximately all of the phenols removed from the oil settling to the bottom and being drawn off and the oil substantially free from phenols being drawn off at the top. The feature of introducing the extracting solution at the second or third plate from the top of the apparatus prevents the loss of such material by entrainment in the tar oil which is drawn off at the top. The feature of introducing the tar oil at a point spaced from the bottom of the apparatus permits the aqueous solution to separate completely from the tar oil whereby it is substantially free from drops of oil mechanically held therein.

The aqueous solvent solution carrying the phenols after having been drawn off from the apparatus is diluted with water in the manner described. The phenols which are substantially insoluble in this dilute solution separate out as a liquid layer which is drawn off. The remaining dilute solution is then concentrated in an evaporator to approximately its original strength for reuse in the practice of the process and the water condensate from the evaporator is employed for further diluting the succeeding solutions of phenols whereby every trace of the phenols which did not separate on dilution is recovered.

The process is preferably carried out at as near atmospheric pressure as possible, no decided advantage being obtained in operating the process at a pressure in excess of that required to provide for the desired flow of liquids. Moreover the process can advantageously be carried out at ordinary temperatures if a solute which gives sufficient solvent character to the water is selected. When employing solutes which give less solvent character to the water it is advantageous to employ somewhat elevated temperatures, for example around 50° C., since the solubility of the solute in water generally increases with the temperature and thereby the solvent character of the water for the tar acids is increased. As indicated by tests conducted the tar acids are not much more soluble in the hot solution than in a cold solution, provided that the concentration of the extracting solution remains the same in both cases. The process can be handled essentially as a closed counter-current system with no substantial expense of operation except the minor expenses attendant upon the evaporation required. A particular advantage of this process

is that it avoids the expense due to the loss of chemicals and to the use of strong acids and alkalis.

In addition to extracting phenols I have discovered that if a strong solution of the solute materials, such as sodium cymene sulfonate, is employed, aromatic hydrocarbons such as benzol may to a certain extent be extracted by my process. The solubility of such hydrocarbons in the extracting solution is pronounced but is not as great as in the case of phenolic compounds. The process is also applicable to the extraction or purification of reduced phenols such as hexahydrophenol; also to dissolving such materials as naphthenic acids and can be applied to the removal of such acids from naturally occurring petroleum oils containing the same. Moreover the process may be applied to the removal of nitrogen bases from shale oils carrying substantial amounts of such bases.

By proper choice of concentrations of the solute in the solvent solution it is practicable to extract fractionally or in series from an oil first a more soluble and then a less soluble constituent, e. g. tar acids and then aromatic hydrocarbons from a tar oil. Also the reverse process may be carried out, e. g. tar acids and aromatic hydrocarbons may first be extracted from a tar oil by means of a relatively concentrated solution of sodium cymene sulfonate, then by proper dilution the dissolved aromatic hydrocarbons caused to separate out and be removed and then by further dilution the tar acids separated out and removed, after which the diluted aqueous solution may be evaporated to the original concentration and reused in the further practice of the process. It will be apparent that if it is so desired the oil may be treated with a plurality of solutions of a solute of the character referred to of progressively increasing strength and each of the resulting solutions diluted with water so that the substantially water insoluble ingredients in the several fractions may be separately recovered.

By the term "salt of a base-forming metal" as employed in the claims is meant a salt of an alkali metal of the character referred to herein and the term includes the hypothetical base-forming metal ammonium.

While I have described in detail the preferred practice of my process it is to be understood that the details of procedure outlined may be widely varied without departing from the spirit of the invention or the scope of the subjoined claims.

I claim:

1. The process of extracting and recovering substantially water insoluble ingredients of ring structure from oils containing the same which comprises treating such oils with a relatively strong aqueous solution of an organic acid salt of a base-forming metal to extract such ingredients therefrom, separating such solution together with the extracted ingredients dissolved therein, diluting such solution, and recovering said ingredients.

2. An extraction process of the character described comprising treating hydrocarbon oils containing substantially water insoluble ingredients to be extracted, with a relatively strong aqueous solution of an organic acid salt of a base forming metal to dissolve such ingredients, separating such solution together with the extracted ingredients dissolved therein from the oil being treated, adding water to such solution to dilute the same, and recovering said ingredients.

3. An extraction process of the character de-

scribed comprising treating oil containing substantially water insoluble ingredients of ring structure to be extracted, with a relatively strong aqueous solution of an organic sulfonate of a base forming metal, separating such solution together with the extracted ingredients dissolved therein from the oil being treated, diluting such solution, and recovering such ingredients.

4. An extraction process of the character described comprising treating oil containing substantially water insoluble ingredients of ring structure to be extracted, with a relatively strong aqueous solution of sodium cymene sulfonate, separating such solution together with the extracted ingredients dissolved therein from the oil being treated, diluting such solution, and recovering said ingredients.

5. The process of extracting and recovering phenols from oils which comprises treating such oils with a relatively strong aqueous solution of an organic salt of a base-forming metal having a pH of less than 13, separating such solution together with the phenols dissolved from the oil being treated, diluting such solution, and recovering the phenols.

6. The process of extracting and recovering tar acids from tar oils which comprises treating such oils with a relatively strong aqueous solution of an organic sulfonate of a base-forming metal, separating such solution together with the tar acids dissolved from the oil being treated, diluting such solution, and recovering the tar acids.

7. The process of extracting and recovering tar acids from tar oils which comprises treating such oils counter-currentwise with a relatively strong aqueous solution of an organic salt of a base-forming metal, separating such solution together with the tar acids dissolved from the oil being treated, diluting such solution, and recovering the tar acids.

8. In a process of the character described for extracting certain substantially water insoluble ingredients of ring structure from oils containing the same, the step of treating such oils with a relatively strong aqueous solution of an organic salt of a base-forming metal to dissolve said ingredients.

9. In a process of the character described for extracting certain substantially water insoluble ingredients from hydrocarbon oils containing the same, the step of treating such oils with a relatively strong aqueous solution of an organic sulfonate of a base-forming metal to dissolve said ingredients.

10. In a process of the character described for extracting certain substantially water insoluble ingredients of ring structure from oils containing the same, the step of treating such oils with a relatively strong aqueous solution of sodium cymene sulfonate to dissolve said ingredients.

11. A process of the character described for extracting and recovering certain substantially water insoluble ingredients from hydrocarbon oils containing the same which comprises treating such oils with a relatively strong aqueous solution of an organic acid salt of a base-forming

metal to dissolve said ingredients, separating such solution together with the extracted ingredients dissolved therein from the oil being treated, and successively diluting and recovering said ingredients.

80

12. The process of extracting and recovering certain substantially water insoluble ingredients of ring structure from oils containing the same which comprises treating such oils with a relatively strong aqueous solution of an organic acid salt of a base-forming metal to dissolve said ingredients, separating such solution together with the extracted ingredients dissolved therein from the oil being treated, and fractionally diluting such solution with water and recovering said ingredients.

85

13. In the herein described extraction process, the step of recovering substantially water insoluble ingredients of ring structure dissolved in a relatively strong aqueous solution of an organic acid salt of a base-forming metal which comprises treating such a solution with water.

95

14. In the herein described extraction process, the step of recovering substantially water insoluble ingredients of ring structure dissolved in a relatively strong aqueous solution of an organic sulfonate of a base-forming metal which comprises treating such a solution with water.

100

15. The process of extracting and recovering certain substantially water insoluble ingredients from hydrocarbon oils containing the same which comprises treating such oils counter-currentwise with a relatively strong aqueous solution of an organic acid salt of a base-forming metal, separating such solution together with the extracted ingredients dissolved therein from the oil being treated, diluting such solution, and recovering said ingredients.

105

16. An extraction process of the character described comprising treating a current of oil containing substantially water insoluble ingredients of ring structure to be extracted, with a counter-current of a relatively strong aqueous solution of an organic acid salt of a base-forming metal to extract said ingredients from said oil, separating such solution together with the extracted ingredients dissolved therein from said oil, diluting such solution, recovering said ingredients, concentrating the diluted solution, and reusing the same in the counter-current treatment.

110

17. The process of fractionally extracting certain substantially water insoluble ingredients of ring structure from oils containing the same which comprises treating such oils with a plurality of solutions of progressively increasing strength of an organic salt of a base-forming metal, diluting the resulting solutions with water, and recovering said ingredients.

115

18. The herein described process of dissolving phenols, aromatic hydrocarbons, naphthenic acids and nitrogen bases such as are found in petroleum oils in an aqueous solvent which comprises mixing the material to be treated with a relatively strong aqueous solution of an organic salt of a base-forming metal.
